APPARATUS FOR POLISHING EXPLOSION ENGINE VALVES

Juan Fernandez Triana, Habana, Cuba, assignor
of one-half to Antonio Eloy Novoa, Mariana, Cuba

Refiled for abandoned application Serial No. 527,595, April 3, 1931. This application September 15, 1934, Serial No. 744,244.

4 Claims. (Cl. 51—29)

This application is a substitute for abandoned application 527,595, filed April 3, 1931.

This invention relates to the operation of polishing the valves of an explosion engine, and it has for object to provide an apparatus for polishing at the same time all the valves of the cover of an explosion engine, which apparatus comprises a plurality of polishing devices of a well known type which are adapted to be individually applied to the valves, and a plurality of gear mechanisms individually connected to said polishing devices for operating them; the result being that the valves to be polished go up and down alternately, whereupon all the valves of the cover of an explosion engine may be polished in less time than an operator would employ in polishing only one of them by the manual means at present known.

The invention is described with reference to the figures in the accompanying drawings, of which: Fig. 1 is a front elevation view of the apparatus. Fig. 2 is a top plan view of the same. Fig. 3 is an end elevation view of the same. And Fig. 4 is a horizontal section on line 4—4 of Fig. 3.

This apparatus consists of a metallic framework 1 supported on a suitable table, and on which frame is slidably mounted a bench 2 adapted to receive the cover of an engine whose valves are to be polished, and the bench can be moved to fore and rear positions transversally of the apparatus.

At the ends of the frame 1 and rearwards the same are affixed two uprights 3 which have their middle portions narrowed and their upper and lower portions enlarged, and on the upper end portions of said uprights 3 and rearwards the same is rotatably mounted on suitable bearings a horizontal driven shaft 4, and at the middle of the upper portions of said uprights 3 is supported a horizontal pivot-shaft 5 parallel to the shaft 4 and on which are oscillatably mounted a series of spaced forked arms 6 which project forward and bear, between the fore ends of their branches, polishing mechanisms which may be of any type known, and which comprise individual gear mechanism 7 which are not described in detail as the same do not form a part of this invention, and which gear mechanisms are adapted to actuate rotatory rods 8 having heads 9 adapted to engage the valves of an explosion engine to cause them to rotate for polishing them by means of the application of a polishing paste between the surfaces of the valve and its seat. On the horizontal shaft 7 of each gear mechanism 7 is mounted a sheave 10, and the various sheaves 10 are respectively provided with endless belts 11 passing around another sheave 12 of smaller diameter fixed on the driven shaft 4. The forked arms 6 rest upon a horizontal bar 13 supported on the fore ends of levers 14 mounted on horizontal pivots 15 sup-

ported on the upper portions of the uprights 3, and which levers are connected at their rear ends, as will hereinafter be described in detail.

On the lower half portion of said uprights 3 is rotatably mounted a horizontal cam-shaft 16 provided with a series of radial cams 17 spaced from each other along the shaft and adopting in their whole a helical arrangement, so that the cams 17 may stand in the vertical cross planes corresponding to the heads 9 of the polishing rods 8. In front of said cams 17, to be actuated by the same, are respectively disposed a series of cam crank-levers 18 oscillatably mounted on a horizontal shaft 19 supported on the fore ends of rocker arms 20 fixed to a horizontal shaft 21 mounted on the lower portion of the uprights 3 below the cam-shaft 16. The three horizontal shafts 16, 19 and 21 are parallel to the driven shaft 4. The shaft 21 has an end connected through a bell-crank 22 with a nut 23 to which is pivotally connected the bell-crank 22, and which nut is slidably mounted on a horizontal screw 24 which is rotatably mounted on a bracket piece 25 fixed at the front of the apparatus by an angle iron 26 to the table which supports the framework 1, said screw 24 being provided at its fore end with a handle 27.

The driven shaft 4 receives its motion from any suitable power source, through a sheave 28 and an endless belt 29, and at the same time the shaft 4 transmits its motion to the cam-shaft 16 by means of a small sheave 30 fixed to said shaft 4 and connected by an endless belt 31 to a sheave of large diameter 32 fixed on a horizontal counter-shaft 33 rotatably mounted at the middle portion of one of the uprights 3, on which counter-shaft 33 is secured another small sheave 34 connected by an endless belt 35 with a sheave of smaller diameter 36 fixed to the cam-shaft 16, thus it being possible that the cam-shaft 16 may rotate slowly, so that the cams 17 may actuate in sequence the several crank-levers 18, causing the fore ends 37 of the crank-levers 18 to go up and down alternatively, which ends have a disk shape, as seen in Fig. 4 of the drawings, and are adapted to receive upon themselves the lower ends of the valve stems when an engine cover is placed on the bench 2.

The rear arms of the levers 14 are connected to the fore ends of the rocker-arms 20, by means of connecting rods 38. For protection of the polishing rods 8 is disposed a double-square shaped guard 39 secured by screws to the ends of the uprights 3. The operation of this apparatus is as follows: Once placed on the bench 2 the cover of an explosion engine whose valves are to be polished, the bench is caused to run towards the uprights 3 until the valves placed in the cover may stand vertically beneath the heads 9 of the polishing rods, so that each head 9 may engage each valve 60

head, as it is well known by the experts in the art, and that the valve stems may respectively rest upon the disks 39 joined to the crank-levers 18. The handle 27 will then be actuated, whereupon 5 the screw 24 will rotate and cause a running of the nut 23 pivotally connected to the bell-crank 22, and this bell-crank will change its angular position, causing a rotation of the shaft 21 carrying the rocker-arms 20 which will shift and go 10 up along its fore end together with the rods 38, and the latter will cause the levers 14 to oscillate in order that the fore ends of said levers carrying the bar 13 serving as a support for the forked arms 6 may come down, whereupon said forked arms 15 will come down by gravity and shift on the pivot-shaft 5 until the heads 9 of the polishing rods 8 engage the heads of the valves of the engine cover. The driven shaft 4 is then caused to move by means of its connection, through the sheave 28 20 and the endless belt 29, to the driven shaft of a suitable power source which may be a small electric motor, and the driven shaft 4 transmits its motion to the sheaves system 30, 32, 34 and 36, whereupon the cam shaft 16 will rotate slowly and 25 cause to shift alternately by means of the cams 17 the crank-levers 18 which will make the valves to be polished go up and down, through the disks 37. At the same time the sheaves 12 will transmit the motion of the shaft 4 to the sheaves 10 of the 30 individual gear-mechanisms 7 by means of the endless belts 11, and the gear mechanisms 7' will cause the polishing rods 8 and their heads 9 to rotate alternately from right to left and vice versa, whereupon the valves of the engine cover 35 will rotate in the same manner, and the polishing of the valves will be finished in a short time.

As seen, by means of this apparatus all the valves of the cover of an engine can be polished at the same time, employing for such operation 40 less time than would be employed by an operator for manually polishing only one valve.

It is obvious that the structure of the apparatus and the construction details of the parts thereof may be varied, without by this reason it may be 45 considered as altered the essential character of the invention, which is such as claimed hereinafter.

What I claim is:

1. An apparatus for polishing explosion engine valves, comprising a supporting framework, a 50 bench on the frame work adapted to support the valve carrying cover of an engine, uprights on the framework, a driven horizontal shaft and a horizontal pivot-shaft parallel to the former shaft, both shafts being mounted on the upper portion of the uprights, a series of polishing mechanisms oscillatably mounted on said pivot-shaft, means for individually operating each of said polishing mechanisms from said driven shaft, a cam shaft rotatably mounted on the lower portion 55 of the uprights, and cam levers oscillatably mounted and adapted to individually receive on their free ends the ends of the valve stems.

2. An apparatus for polishing explosion engine valves, comprising a supporting framework, a 60 bench on the framework which is adapted to support the valve carrying cover of an engine, uprights on the framework, a driven horizontal shaft and a horizontal pivot-shaft, both shafts being mounted on the upper portion of the uprights, a series of polishing mechanisms oscillatably mounted on said pivot-shaft, individual means for operating each of said polishing mechanisms from said driven shaft, a shaft having spaced 65 cams in helical arrangement on the same and rotatably mounted on the lower portion of the uprights, a handle for causing the rotation of the 70 screws, rods connecting the pivot-shaft supporting ends of the rocker-arms to the opposed ends of the levers carrying the bar supporting the arms carrying the polishing mechanisms, and means for giving a slow-rotating motion to the cam shaft from said driven shaft.

uprights, a second horizontal pivot-shaft, cam levers oscillatably mounted on this second horizontal pivot-shaft, shifting means for supporting said second pivot-shaft to control the height of the position of the free end of said cam levers, in order that the free ends of said cam levers may individually receive the ends of the valve stems, and means for giving a slow-rotating motion to the cam shaft from said driven shaft.

3. An apparatus for polishing explosion engine 10 valves, comprising a supporting framework, a bench 15 slidable on the framework and adapted to support the valve carrying cover of an engine, uprights on the framework, a horizontal driven shaft and a horizontal pivot-shaft in parallelism and both mounted on the upper portion of the uprights, a series of polishing devices, shifting means 20 for supporting the polishing devices on said pivot-shaft, individual means for operating each of said polishing devices from said driven shaft, a shaft 25 having spaced cams in helical arrangement on the same and rotatably mounted on the lower portion of the uprights, a second horizontal pivot-shaft parallel to the cam shaft, crank-levers oscillatably mounted on said second pivot-shaft, shifting 30 means for supporting said second pivot-shaft to control the height of the position of the free end of said crank-levers in order that the free end of said levers may individually receive the ends of the valve stems, connecting means between the supports for the polishing mechanisms and the supports for the cam levers so that when the former are lowered the latter are raised, and means for giving a slow-rotating motion to the cam shaft from said driven shaft.

4. An apparatus for polishing explosion engine 35 valves, comprising a supporting framework, a bench 40 slidable on the framework and adapted to support the valve carrying cover of an engine, uprights on the framework, a horizontal driven shaft and a horizontal pivot-shaft in parallelism and both mounted on the upper portion of the uprights, a series of forked arms oscillatably 45 mounted on the pivot-shaft, a series of polishing mechanisms individually mounted on each of said oscillatably forked arms, levers pivotally mounted on the upper portion of the uprights and carrying a longitudinal bar adapted to serve as a support for the arms carrying the polishing devices, individual means for operating each of said polishing mechanisms from said driven shaft, a shaft 50 having spaced cams in helical arrangement on the same and rotatably mounted on the lower portion of the uprights, a second pivot-shaft parallel to the cam shaft, crank-levers oscillatably 55 mounted on said second horizontal pivot-shaft, rocker-arms supporting said second pivot-shaft and mounted on a horizontal shaft parallel to the cam shaft and rotatably mounted on the lower portion of the uprights, a system of 60 slidable nut and rotatory screw, a bell-crank fixed to the horizontal shaft carrying the rocker-arms and pivotally connected to said nut to control the height of the position of the free end of said crank-levers, in order that the free end of said levers may individually receive the ends of the valve stems, a handle for causing the rotation of the 65 screws, rods connecting the pivot-shaft supporting ends of the rocker-arms to the opposed ends of the levers carrying the bar supporting the arms carrying the polishing mechanisms, and means for giving a slow-rotating motion to the cam shaft from said driven shaft.
